PONTOON MOTORBOAT

Louis N. Bell, Ronald R. Harris, and Helen E. Harris, Sault Ste. Marie, Mich.

Application April 2, 1942, Serial No. 437,424

5 Claims. (Cl. 114—66.5)

This invention relates to pontoon motor boats, and has for one of its objects the production of a simple and efficient means for adapting the type of pontoon house boats disclosed in the patent issued September 29, 1931, to Louis N. Bell, Number 1,825,613, to meet the special requirements for modern motor boat design.

A further object of this invention is the production of a specially designed hull having a semi-bulb-shaped front nose-piece which cuts down air and water resistance.

Another object of this invention is the provision of an efficient pontoon motor boat wherein a planing fin is located on each side of the front nose-piece of the hull to permit the boat to plane more quickly and to provide a lifting surface while the boat is travelling at a relatively slow speed.

A still further object of this invention is the production of a boat wherein a stationary plane is located at a selected position or positions on the pontoon at a selected angle to suit the particular requirements of each individual boat to lift the pontoon a desired distance out of the water, thereby decreasing draft and increasing speed.

Other objects and advantages of the present invention will appear throughout the following specification and claims.

In the drawings:

Figure 1 is a side elevational view of the improved pontoon motor boat;

Figure 2 is a front elevational view;

Figure 3 is a fragmentary rear elevational view, certain parts being shown in section; Figure 3^a is a fragmentary rear elevational view of a modified form of the invention;

Figure 4 is a fragmentary perspective view of the rear end of one of the pontoons;

Figure 5 is a horizontal sectional view taken on line 5—5 of Figure 3;

Figure 6 is a perspective view of one of the supports for connecting the hull to the pontoons;

Figure 7 is a vertical sectional view taken through one of the supports shown in Figure 6, taken on line 7—7 of Figure 5;

Figure 8 is a vertical sectional view taken on line 8—8 of Figure 5;

Figure 9 is a sectional perspective view taken on line 9—9 of Figure 8;

Figure 10 is a vertical sectional view taken on line 10—10 of Figure 1;

Figure 11 is a side elevational view of one of the adjustable fins, a portion of the supporting pontoon being shown in longitudinal section;

Figure 12 is a vertical sectional view taken on line 12—12 of Figure 11;

Figure 13 is a horizontal sectional view taken on line 13—13 of Figure 11;

Figure 14 is a bottom plan view of a modified type of the invention showing a structure embodying three pontoons.

By referring to the drawings, it will be seen that 15 designates the hull of the motor boat having a suitable superstructure 16 at the top thereof. The hull 15 is provided with a semi-bulb-shaped nose 17 at the front thereof and suitable windows 18 and 18^a are provided in the hull 15 and the superstructure 16.

The hull 15 is supported upon a plurality of parallel spaced pontoons 19 which may be in any suitable number to suit the requirements of the particular type of hull structure, two or three pontoons being preferable. Two pontoons may be utilized, as shown in Figures 1 to 5 inclusive, or three pontoons may be utilized, as shown in the modified form illustrated in Figure 14.

The pontoons 19 carry a plurality of forwardly and upwardly inclined hollow supporting members or tubes 20, and each tube 20 is provided with a lower flange 21 which is welded or otherwise secured to the upper face of the pontoon 19, as shown in detail in Figures 7 and 8. Each tube 20 is also provided with a flange 22 at its upper end which may be riveted or otherwise secured to a suitable frame 23, which frame 23 is carried by the bottom of the hull 15.

Each pontoon 19 is provided at its forward end with a forwardly and upwardly inclined planing fin 24 which extends at a suitable incline with respect to the longitudinal axis of the pontoon 19, as shown in Figure 1, and is preferably of the same width as the pontoon 19 shown in Figure 2, each fin 24 having a stationary plane 25 which extends at right angles to the planing fin 24 and forwardly and downwardly thereof, and preferably being located at the center of the planing fin.

Each pontoon 19 also carries a hinged planing fin 26 hinged as at 26' or in any other suitable manner preferably located intermediate the ends thereof and which planing fin is mounted to move from the full line position shown in Figure 11 to the dotted line position shown in said figure, and each fin 26 may be adjusted by means of a suitable adjusting rod 27, which rod 27 may be set at a proper position by means of a suitable setting device 28 of a suitable type. Each pontoon 19 is provided at its rear end with a downwardly inclined flattened tail portion 29, as shown in detail

in Figure 4, the purpose of which will be herein-after described. Any suitable or desired type of driving means may be employed for driving the propeller 30 which may be carried at a suitable point preferably at the rear end of each pontoon 19. The middle keel 31 is placed longitudinally of and parallel to and preferably at a central position between the adjoining pontoons, as shown. The various parts of course may be suitably braced and the frame 23 may be provided with suitable angle braces 32, as shown in detail in Figure 3.

Each pontoon 19 also carries intermediate the forward and rear ends thereof, and preferably located at the rear of the adjustable planing fin 26, as shown in Figure 1, a vertically slideable adjustable fin 33 which consists of a flat plate having spaced notches 34 on its front edge, and spaced notches 35 on its rear edge to be engaged by transverse locking pins 36 and 37, respectively, 15 to hold the fins 33 in a proper set position. Additional anchoring means 38 may be carried by the top of each pontoon for receiving locking pins 39, which pins also pass through suitable apertures 40 which are arranged in the fin 33 to assist in supporting the fin in a proper position. The pins 36 and 37 engage suitable bars 37a which are carried within the pontoons 19—Note Figures 11 to 13, inclusive. That portion of each pontoon through which the fins 33 extend may be sealed by means of partitions 19a, to prevent flooding of the pontoons, or the pontoons may be constructed in any suitable manner to provide a sealed passageway through which the fins 33 may extend.

If desired, a propeller 30a may be carried by the middle keel 31a, as shown in Figure 3a instead of a propeller being provided at the rear of each pontoon.

A suitable rudder 41 may be carried by the boat and supported in any suitable or desired manner and operated in any convenient manner from the steering control which may be of any conventional type.

It should be noted that the particular shape of the rear end 29 of each pontoon 19 wherein a flat rear edge 29a is provided, as shown in Figure 4, and is provided with a downward slant toward the rear. Because of this structure, as the boat speed increases, the rear portion of the boat will be raised, thereby enabling the boat to plane and increase the speed.

Furthermore, it should be noted that by means of the device illustrated, a strong bracing system is provided. Because of the shape of the device, which eliminates all corners, less wind and water resistance is present. By combining the pontoons and superstructure into a single unit wind and air resistance and bracing is diminished, and the entire boat is reinforced into one unit. The oval or circular tubular braces on the pontoons offer less wind and water resistance and add additional strength and may be placed at frequent intervals to meet the needs of the particular type of boat construction. These braces are preferably welded to the pontoons as described, and bolted to the frame or girders to facilitate repair or replacement. The particular design or arrangement of the girders may be varied to suit the particular type of structure, but the floor girders may be welded or bolted as described to the curved girders of the upper structure, and the curved section between the pontoons. Many types of bracing and framework may be employed without departing from the spirit of the invention and it is not desired to limit the present invention to such par-

ticular design and arrangement of framework structure.

It is important to note, however, that the present invention embodies the feature of an adjustable fin which may be fastened at any position upon the pontoon and may be lowered to a desired depth which the weather and other conditions may require. This type of fin has much the same function as the keel on a sail-boat and offers increased stability in rough weather, although the multiple points of balance on a pontoon boat make it exceptionally stable. This type of fin particularly shown in Figure 11 enables a pontoon boat to retain the stability of crafts with deeper draft, and at the same time enables the craft to enter shallow water. A further important feature of the invention is the type of adjustable plane 26 which may be used upon each pontoon and located in a suitable position and may be raised or lowered to the position best suited to the individual type of boat to plane the same efficiently regardless of change in load or weather.

It should be understood that certain detail changes in the mechanical construction, and arrangement of parts may be employed without departing from the spirit of the invention so long as such changes fall within the scope of the appended claims.

Having described the invention, what is claimed as new is:

1. In a boat, a pontoon structure comprising a plurality of spaced parallel pontoons, a hull supported above said pontoons, a keel located between said pontoons, each pontoon having a rounded formed nose, an upwardly and forwardly inclined flat stationary planing fin carried by the formed end of each pontoon, the lower ends of the planing fins extending below the pontoons, and a right-angularly extending fin located centrally of and extending upwardly relative to each first mentioned fin and terminating short of the lower ends of the first mentioned fins.

2. In a boat, a pontoon structure comprising a plurality of spaced parallel pontoons, a hull supported above said pontoons, a keel located between said pontoons, each pontoon having a rounded formed nose, an upwardly and forwardly inclined stationary planing fin carried by the formed end of each pontoon, an adjustable forwardly and upwardly inclined planing fin suspended below the bottom face of each pontoon and located intermediate the ends of each pontoon, and a fin arranged in a vertical plane carried intermediate the ends of each pontoon, and means for holding said last mentioned fin in a selected vertical position.

3. In a boat, a pontoon structure comprising a plurality of spaced parallel pontoons, a hull supported above said pontoons, a keel located between said pontoons, each pontoon having a rounded formed nose, an upwardly and forwardly inclined stationary planing fin carried by the formed end of each pontoon, an adjustable forwardly and upwardly inclined planing fin suspended below the bottom face of each pontoon and located intermediate the ends of each pontoon, an operating rod engaging said adjustable planing fin for holding said planing fin in a selected position, said operating rod extending above said pontoon for convenient operation by an operator, and a vertically adjustable fin arranged in a vertical plane carried by each pontoon rearwardly of said adjustable forwardly and upwardly inclined planing fin.

4. In a boat, a pontoon structure comprising a

plurality of spaced parallel pontoons, a hull supported above said pontoons, a keel located between said pontoons, each pontoon having a rounded formed nose, an upwardly and forwardly inclined stationary planing fin carried by the formed end of each pontoon, and a flat vertically adjustable fin extending in a vertical plane through the central vertical axis of each pontoon and located near the rear end of each pontoon.

5. In a boat, a pontoon structure comprising 10 a plurality of spaced parallel pontoons, a hull supported above said pontoons, a keel located be-

tween said pontoons, each pontoon having a rounded formed nose, an upwardly and forwardly inclined stationary planing fin carried by the formed end of each pontoon, and the rear of each 5 pontoon having a downwardly turned portion, said portion having a forwardly and upwardly inclined rear face terminating in a transverse horizontal straight rear end.
